Specification of Letters Patent. Patented Aug. 17, 1920.

Original application filed July 26, 1917, Serial No. 182,817. Divided and this application filed March 9, 1918. Serial No. 221,343.

To all whom it may concern:

Be it known that we, WILLIAM V. D. KELLEY, a citizen of the United States, and resident of Brooklyn, county of Kings, and State of New York, and JOSEPH MASON, a citizen of the United States, and resident of New York city, county of New York, and State of New York, have invented certain new and useful Improvements in Photographic Images, of which the following is a specification.

This invention relates to photographic images, and has particular reference to the manufacture of projecting positive film in color motion picture reproduction. This application is a division of application No. 182,817, filed July 26, 1917.

In manufacturing projecting positives from color value records made by exposures through color screens, and especially where the positive is to have one color value record exactly registered with another on the same image area, a number of practical difficulties are encountered in obtaining the necessary accuracy of registry and printing. Celluloid film is affected by liquids, humidity, age, etc., and has a general tendency to shrink. A negative after being developed and dried, and with age, is always shorter and narrower than the comparatively fresh positive, and will also vary from time to time with humidity, and from place to place by reason of unequal tension in drying. Owing to these variations, it has been difficult to produce superposed color value records in registry with sufficient accuracy to give satisfactory commercial results when projected in colors on the curtain. The necessity of obtaining exact registry of the two images on a single image area is at the very foundation of the art of producing natural color films running at standard speed in ordinary projectors wherein one coating carries an image recording one color family, and the other coating an image recording a complementary color family. The very slightest relative displacement of the images results in loss of sharpness and perspective, similarly to lack of focus. This also affects the accuracy of color rendering, especially with the subtractive system wherein the black silver positive images are rendered transparent and dyed or otherwise colored. It is therefore extremely important that a posi-

tive film product be provided capable of 55 being colored by any of the known suitable methods, which will have uniform accuracy of registration throughout a long strip, so that when enlarged in projection to 200 or more times, the two images will appear as 60 one without any blurring, or fringe, or loss in sharpness and perspective.

By this invention a positive strip is provided having one or more images printed on each image area with extreme accuracy. 65 This result is produced by effecting registration of the negative with the sensitive positive strip, solely by the perforations, and particularly by a registering pin or pins at the printing window. The same registry of 70 other negatives printed on that positive area is retained by using the same pin and perforation as a standard. In employing standard film provided with perforations at the sides, we use one perforation on one 75 side solely for longitudinal registry, and a perforation on the other side for both longitudinal and lateral registry. The latter registration is by a pin completely filling the elongated standard film perforation of 80 both positive and negative, and the former registration is by a pin filling a like perforation of both from top to bottom but not from side to side. Since all of the negative and positive areas will have like perforations, 85 any number of images can thus be superposed, registered accurately at the printing window solely by perforations, and then printed.

The standard practice to-day is to perforate both negative and positive with the same make of perforator, so that initially the four perforations on each side are alike in shape and spacing. After the negative has been developed and dried, it is evident 90 that if one of the eight positive and negative perforations are exactly registered, the others will all be out of registry by the amount of variation of the negative relatively to the fresh positive. The full fitting 95 pin will thus exactly register these two perforations, while the opposite loose fitting pin can register two corresponding perforations of positive and negative from top to bottom only, as the negative shrinkage will 100 throw the sides out of registry. The novel product of the foregoing method is thus 105 characterized by the images being always at

one side of the positive area by an amount equal to the shrinkage of the negative relatively to the fresh positive at the time of printing, in contradistinction to the previous 5 efforts in this art to exactly center the image on the positive, or varying from side to side as well as longitudinally on each image area. Standard eight hole motion picture film embodying this invention will also show a characteristic 10 positioning of the images longitudinally of the film above or below the median transverse line of each picture area, depending upon which hole is chosen as the standard.

15 Figure 1 is a detail of the registering mechanism,

Fig. 2 is a front view of Fig. 1, seen from the right,

Figs. 3 and 4 are detail views showing 20 the separate vertical and horizontal registering mechanism,

Fig. 5 is an elevation showing one printing of a double coated positive, negative emulsion to positive emulsion,

25 Fig. 6 is an elevation showing the other printing negative base to positive emulsion and

Fig. 7 is a perspective of a double printed film.

30 1 is a negative emulsion on transparent perforated base 2. 3 is the positive perforated base having emulsions 4, 5, thereon to be printed. The first printing may be as shown in Fig. 5 with negative emulsion to 35 positive emulsion, and the second printing as shown in Fig. 6, with negative base to second positive emulsion, and producing when developed, the positive shown in Fig. 7 having images on each side. This invention is applicable to ordinary black and 40 white printing on single coated emulsion, but is especially intended for color reproduction where the image on one side of the positive is of one color family and that 45 on the other side is of a complementary color family, such images requiring to be in register for projection.

In employing standard film provided with 50 perforations at the side, we use a certain perforation of each positive image area at the printing gate as a standard, and use the corresponding perforation of each negative for registration therewith by a pin tightly fitting the perforation from end to 55 end and top to bottom, so that any negative shrinkage, warping or distortion is all taken up at this standard perforation. With standard perforations, this single pin will definitely register the negative both laterally 60 and longitudinally, but in practice we preferably use a second co-operating pin which fits corresponding opposite perforations of positive and negative tightly from top to bottom but loosely from side to side so as to allow the shrunk negative to slide later-

ally under the control of the full fitting pin. This second pin consequently only assists the longitudinal registration and acts independently of, although simultaneously with, the full fitting pin. As soon as registered, 70 the films are clamped in printing contact by a reciprocatory clamp 13, and printed, emulsion to emulsion. The clamp also carries the registering pins 8, 10, and is reciprocated by any suitable means. Feeding of 75 the films is controlled so that like color family images will be registered and printed in succession on the first positive emulsion, and all of the complementary color family images on the second positive emulsion. In 80 printing the other side of the positive both the positive and negative are reversed, bringing the negative base 2 to second positive emulsion 5, as shown in Fig. 6. The pins 8, 10, are also reversed, so that the 85 holes 7 and 12 in the positive retain the same relation with the pins 8, 10, as before, but now register the holes of the second negative with the positive holes 7, 12, respectively. After the strips are registered 90 and clamped, the exposure is made by light through window 9, either by a hand or power driven shutter moving in front of a suitable light. The positive strip is then developed, fixed, and washed on both sides 95 at once, and now contains color values of one family all on one side, and color values of another family all on the other side, but each registered longitudinally with one certain perforation in the positive and independently registered laterally with another certain perforation therein. If the ordinary single image positive is to be made, the negative and positive are fed, registered, clamped and printed together. In printing 100 double coated positives, suitable precautions will be observed to prevent fogging of one side in printing the other, our preferred method being to provide relatively "slow" emulsions on the positive with quick exposure to light of proper strength. 110

The terms "negative" and "positive" are used in the relative sense herein, and not as limitations upon the invention, which can not only be used specifically for making 115 colored projecting transparencies for motion picture reproduction, but can also be used for various other purposes, such as ordinary black and white positives, or single pictures. Positives made by this invention will be so 120 accurately registered as to run much more smoothly than positives printed without being registered at the printing window.

So far as we are aware, one or more images registered with predetermined perforations in opposite edges of a strip have not heretofore been produced, and we believe ourselves to be the first inventors of such product, as well as a transparency carrying a plurality of images, each registered with

predetermined perforations in the edges of such transparency, in a position determined by taking up all negative shrinkage on one side.

5 What is claimed, is:

A photographic film strip transparency having a series of image areas, each area

carrying a plurality of color value printed images, each image being similarly registered longitudinally with a certain perforation and laterally with a certain other perforation of the film strip.

WILLIAM V. D. KELLEY.
JOSEPH MASON.
